UNITED STATES PATENT OFFICE.

JAMES W. STIRTON, OF DETROIT, MICHIGAN.

HYDROCARBON-BURNER.

1,161,546.

Specification of Letters Patent.

Patented Nov. 23, 1915.

Application filed May 26, 1915. Serial No. 30,491.

To all whom it may concern:

Be it known that I, JAMES W. STIRTON, a citizen of the United States, and a resident of the city of Detroit, in the county of Wayne and State of Michigan, have invented certain new and useful Improvements in Hydrocarbon-Burners; and I do hereby declare that the following is a full, clear, and exact description of the same, reference being had to the accompanying drawings, and to the numerals of reference marked thereon, which form a part of this specification.

This invention relates to an improved type of hydro-carbon burner embracing a number of novel features of construction and operation, and operating at high efficiency to perform the purpose for which designed.

It is an object of this invention to construct a burner embracing an improved arrangement of fuel supply and generator pipes, as well as an improved type of outlet nozzle from which the fluid issues for combustion.

It is also an object of this invention to construct a burner embodying an improved arrangement of generator pipes and air supply means to insure complete combustion of a hydro-carbon fluid with an intensely hot and clean flame, the arrangement further permitting detachment and removal of the generator supply pipe as a whole for cleaning by simply loosening a union joint and without disturbing other parts of the device.

It is furthermore an important object of this invention to provide a burner construction wherein an improved type of base associated with a novel arrangement of burner pipes and burner is provided, and with drip pans for generating purposes having air ducts associated therewith in a manner for most efficient operation in securing complete combustion.

It is finally an object of this invention to construct a burner simple in construction, and operating efficiently to effect complete combustion of the fuel at all degrees of regulation.

The invention (in a preferred form) is illustrated in the drawings and hereinafter more fully described.

In the drawings: Figure 1 is a top plan view of a double burner embodying the principles of my invention. Fig. 2 is a section taken on line 2—2 of Fig. 1, with parts shown in elevation and with parts omitted.

Fig. 3 is a detail section taken on line 3—3 of Fig. 1. Fig. 4 is an end view of the burner.

As shown in the drawings: The reference numeral 1, indicates as a whole a metal base which is shown as rectangular in shape, though not necessarily so, and formed on the upper surface of said base are circular ribs 2, each forming in the area confined thereby a drip pan into which the oil is poured for generating purposes. Formed on the upper surface of said base 1, which preferably may be a casting, within the area confined by said circular ribs 2, are inlet air nozzles 3, there being two formed on each of the drip pans and one disposed diametrically opposite the other.

An aperture 4, is provided in the surface of the top wall of said base 1, and between the respective nozzles 3, at the center of each of the drip pans formed by the ribs 2, the metal surrounding said apertures 4, as clearly shown in Fig. 2, being formed upwardly therearound from the surface of the drip pan to prevent oil poured into the drip pan from flowing therefrom through said apertures.

As shown in the figures, the base 1, is formed for two burners, and two generator supply pipes of U-shape are provided, the upper or generator branch thereof denoted by the reference numeral 5, and extending diametrically over the drip pan between the air nozzles 3, as clearly shown in Figs. 1 and 2, and the other branch 7, thereof, of each of said pipes extending downwardly through a central opening 6, in the top wall of the base 1, and bent inwardly terminating at a point beneath the central apertures 4, of each of the drip pans formed on said base. The branch 5, of each of said pipes is connected into an elbow 8, which is in turn connected to a short pipe section 9, connected into a union 10, which serves to connect said pipe section to a supply line 11, each provided with valves 12, as shown in Fig. 1, and connected to one another at a T 13, which leads to a main supply line 14. Threaded on the end of the branch 7, of each of the generator supply pipes, is a cap 15, having an aperture 16, in the wall thereof adapted to be registered directly beneath said aperture 4, in the top wall of the base, affording an outlet nozzle for fuel admitted to be burned through said branch pipe 5—7.

Secured in any suitable manner upon the

inner surface of one of the side walls of the base 1, as shown in Fig. 3, is a bracket 17, affording a drip pan 18, disposed directly beneath the cap 15, so that in the event of 5 an overflow of fluid through the nozzle 16, the same will drip downwardly and be caught in said drip pan 18, and eventually evaporated and drawn upwardly through the aperture 4, or through the air inlet 10 nozzles 3.

Attached upon the branch pipe 5, is a deflector or baffle plate 19, disposed directly above the drip pan, and toward which the various passages through which the fluids 15 flow are directed, the fluids intermingling with one another and being deflected around the edges of said plate.

The operation is as follows: The supply 20 of fuel from the pipes 11, to the burners is governed by the valves 12, and in starting the burners a quantity of fuel is first poured into the drip pan formed in the upper surface of the top wall of the base 1, and the same ignited, thereby heating the branch 5, 25 of the supply pipe. The novel arrangement of air inlet nozzles 3, permits a supply of air to be directed into the jet of fluid for combustion issuing from the nozzle opening 16, together with that air passing inwardly and 30 upwardly through the aperture 4, with the fuel to insure complete combustion of the fuel with a hot, clean flame. The size of the flame is not only due to the adjustment of the valve 12, but depends to some extent 35 upon the size of the aperture 16, in the cap 15, and it is obvious that different caps 15, may be used, having different sized apertures or nozzles therethrough, whereby the maximum size of flame for fuel consumed 40 may be pre-determined. The union 10, permits the generator supply pipe 5-7, to be readily detached for cleaning, and the entire structure, due to the arrangement of the parts, is easily accessible at all points. The 45 deflector or baffle plate 19, serves further to intermingle the air with the fuel as the same pass upwardly through the respective passages provided therefor, to insure complete combustion thereof, and also acts to distribute 50 the heat to the generator pipe by preventing concentration and direct application of the flame to one point on the pipe.

I am aware that various details of construction may be varied through a wide 55 range without departing from the principles of this invention, and I therefore do not purpose limiting the patent granted otherwise than necessitated by the prior art.

I claim as my invention:

60 1. In a burner of the class described a base, a rib formed on the upper surface thereof, said base having a central aperture and a relatively large opening therethrough, a generator supply pipe extending above said base and downwardly through

said opening therein to a point beneath said central aperture in said base, a nozzle on the end of said pipe to admit a flow of fuel upwardly through said central aperture, and air supply nozzles formed on said base 70 on each side of said central aperture to admit air into the region of upward flow of the fuel to permit combustion thereof, and to heat the generator branch of said generator supply pipe.

2. In a device of the class described a base, a circular rib formed thereon affording a drip pan on the top wall of said base, said base having an opening and a central aperture therethrough, a rib around said aperture to prevent loss of liquid fuel therethrough from said drip pan, a generator supply pipe extending above said base over said aperture and downwardly through the opening in said base to a point beneath said aperture, a nozzle on the end of said pipe to admit fuel through said central aperture, and means formed on said base on each side of said central aperture admitting a flow of air into the region of fuel supply to insure 80 combustion of the fuel beneath the generator branch of said pipe.

3. In a device of the class described a base, drip pans formed in the upper surface thereof, air supply nozzles formed within 85 said drip pans and projecting upwardly from the surface thereof, said drip pans each having a central aperture therethrough, a rib around each aperture to prevent the contents of the drip pan draining 100 therethrough, generator supply pipes extending above said drip pans and downwardly through a common opening in the base between said drip pans to points beneath said central apertures of said drip 105 pans, nozzles on the ends of said pipes to admit fuel upwardly through the central apertures in said drip pans, and deflector plates secured upon the generator branches of said generator supply pipes directly above 110 the central aperture in the drip pans to receive the flame, due to combustion impinging thereon.

4. In a device of the class described the combination with a base affording drip 115 pans and having a central aperture and an opening therein, of a generator supply pipe extending above said base and downwardly through the opening to a point beneath the central aperture in said base, a fuel nozzle on the end of said pipe detachable therefrom, and air inlet passages formed in the top wall of said base on each side of said central aperture and directed toward the axis thereof to intermingle with 120 the fuel passing upwardly through said central aperture.

5. In a device of the class described the combination of a base and air nozzles formed therein, of a U-shaped generator 125

supply pipe, one branch disposed above the base and the other below, a removable apertured cap affording a nozzle on the end of said pipe, and a baffle plate secured to the 5 upper generator branch of said pipe to receive a flame from the nozzle impinging thereon to distribute the heat to the generator branch of said pipe.

6. The combination with a generator supply pipe, of a base having an aperture therethrough, a drip pan formed in said base surrounding said aperture, a nozzle on the end of said generator supply pipe disposed beneath said aperture to admit fuel there- 5 through, and convergently arranged air nozzles formed in said base within said drip pan on each side of said central aperture and directed toward the axis thereof.

7. In a device of the class described the combination with a base having a common 20 central opening therethrough and drip pans formed on the surface of said base on each

side of said opening, said base having nozzle apertures centrally disposed within said drip pans, a rib around said apertures to 25 prevent leakage of liquid fuel in said drip pans through said apertures, upwardly projecting air nozzles formed within each of said drip pans on each side of the aperture therein, generator pipes each curving down- 30 wardly through the common opening and inwardly beneath the respective apertures in said base and a nozzle on the ends of said pipes to admit fuel upwardly through said apertures for combustion with air ad- 35 mitted through said air nozzles.

In testimony whereof I have hereunto subscribed my name in the presence of two subscribing witnesses.

JAMES W. STIRTON.
